SAMUEL F. ARBUCKLE, OF INDIANAPOLIS, INDIANA, ASSIGNOR TO UNITED STATES AUTOMOTIVE CORPORATION, OF CONNERSVILLE, INDIANA, A CORPORATION OF DELAWARE.

LAMP CONSTRUCTION.

1,376,599.

Specification of Letters Patent.

Patented May 3, 1921.

Application filed March 14, 1919. Serial No. 282,680.

To all whom it may concern:

Be it known that I, SAMUEL F. ARBUCKLE, a citizen of the United States, and a resident of Indianapolis, county of Marion, and State of Indiana, have invented a certain new and useful Lamp Construction; and I do hereby declare that the following is a full, clear, and exact description thereof, reference being had to the accompanying drawings, in which like numerals refer to like parts.

This invention relates to electric headlights for automobiles, launches and the like, and more specifically to the construction of tiltable or adjustable reflectors.

In the actual use of headlights or lamps using tiltable reflectors great difficulty has been found in preventing dust or moisture from seeping in to the lamp casing either through the joint made by the front glass and the demountable glass or lens rim, or through other portions of the lamp casings through which the electric circuit or operating mechanism extends. Dust and moisture are very detrimental to the reflector and will soon tarnish or dirty it to such an extent that it will lose a great portion of its reflecting property. It is proposed in this invention to overcome these difficulties by providing a construction whereby the reflector will be sealed against dust and moisture when in its adjusted position. This is accomplished by sealing flanges which are engaged and sealed by the reflector when in its adjusted position engaging therewith.

Still another feature of this invention is the manner of supporting or hinging the reflector, so as to be tiltable and adjustable in the lamp casing and frame, which permits a simplicity of construction which has considerable manufacturing advantages.

A further feature of this invention relates to a fluid actuated means for controlling the reflector, which consists of a bellows or collapsible disks which may be mounted between the reflector and casing so as to take up a minimum amount of space and provide a maximum displacement. Such a construction would, in addition to these features, eliminate any possibility of leakage such as may occur in the use of pistons, and would not necessitate the provision of lubricating means necessary in pistons and like fluid actuating mechanisms. The amount of space taken up by a bellows would be so small as to eliminate any necessity of re-

constructing the common type of lamp casing or provide a projecting housing for inclosing said actuating means.

In the accompanying drawings which are made a part of this application Figure 1 is a central vertical cross section through the lamp casing and reflector showing the reflector in its normal position. Fig. 2 is the same as Fig. 1 showing the reflector in its forward or downward position. Fig. 3 is a modified form of the upper portion of the lamp. Fig. 4 is a section taken on the line 4—4 of Fig. 1.

There is shown herein a lamp casing 10 formed of one piece and provided with a flat periphery 11 adjacent its open face, and an inturned flange 12. Adapted to fit snugly over the periphery 11 there is a lens holding rim or door 13 on which is secured a flange member or ring 14 in which the lens 15 is secured. A rim 16 is provided so as to be secured between the lens 15 and the inturned flange 12, which is provided with a recess in which a sealing member 17 is engaged so as to be squeezed between the inner surface of the lens and said rim so as to protect the lens from dust or moisture which may seep into the lamp. The rim 16 extends inwardly at the lower portion of the lamp, and is provided with an inwardly extending flange about its periphery, said flange extending upwardly at an angle to the lens, corresponding to the angle at which the reflector is to be tilted. Lying adjacent to the rim 16 and in close contact therewith there is a flange member 18 which telescopes with said rim on the lower portion thereof and is provided with an inwardly turned flange 19 parallel to the lens 15 of the lamp.

The reflector 20 is provided with projections 21 on the lower side thereof which are adapted to extend through corresponding openings at the bottom of the flange member 18 on both sides of the pivotal center thereof so as to form pivotal hinges. The periphery of the reflector has an outwardly turned flange 22 which engages and seals against the flange 19 when the reflector is in the position shown in Fig. 1 and which engages and seals against the flange of the rim 16 when in the position shown in Fig. 2.

It will therefore be seen from the foregoing that the dust and moisture is prevented from entering the reflector through the sealing joints and flanges of the rim 16 and 110

member 18 when the reflector is in its forward position as shown in Fig. 2 or its normal position as shown in Fig. 1.

The lamp is further provided with a lamp bulb 23, a lamp socket 24 extending through the rear of the reflector and connected electrically by the flexible wires 25. The return movement of the reflector to normal position is accomplished by the bellows 26 which are controlled by suction from the motor or other means through the conduit 27. There is a spring 29 secured to the upper portion of the lamp casing and adapted to engage and exert a pressure against the projection 28 on the reflector for tilting it forward when the suction in the bellows is released and keeping the pivotal hinge in its proper position and preventing its disengagement. However, the spring 29 is adapted to be easily overcome by the suction of the bellows for returning the lamp to normal position from tilted position. Fig. 3 shows a modified form of protecting flange, wherein the flange 19 is recessed to receive a bead 30 on the upturned flange 22 of the reflector, whereby the reflector is always held in its proper position and protected from the elements.

The invention claimed is:

- 30 1. The combination with a lamp casing and a lens therefor, of a reflector within the lamp casing having an outwardly extending flange at its edge, a flange member carried in the lamp casing having a flange for engaging the reflector flange when in normal position, and a rim secured between said flange member and lens for engaging the reflector flange when in its forward position, and a gasket in conjunction therewith for protecting said reflector from dust and moisture.
- 35 2. The combination with a lamp casing, and a lens therefor, of a reflector within the lamp casing, a downwardly extending projection on the lower portion of said reflector, a flange member secured to the lamp casing having a flange for engaging the reflector flange when in normal position, through which said projection extends for pivotally mounting said reflector within said casing, a rim between said flange member and lens for engaging the reflector flange when in its forward position, and a gasket in conjunction therewith for protecting said reflector from dust and moisture.
- 40 3. The combination with a lamp casing,

and a lens therefor, of a reflector within the lamp casing having a downwardly extending projection on the lower portion thereof, means within said casing in which said projection is mounted for pivotally supporting said reflector and yielding means for retaining said projections in pivoted position for permitting it to be tilted within said casing.

4. The combination with a lamp casing 65 and a lens therefor, of a reflector within the lamp casing, a reflector mounting, means on said reflector adapted to engage said mounting for pivotally supporting said reflector therein, and yielding means for holding said 70 reflector in pivotal relation with said mounting.

5. The combination with a lamp casing, and a lens therefor, of a reflector within the lamp casing, means on the lower portion of 75 said reflector for pivotally supporting it within said casing, and yielding means for engaging said reflector for exerting a downward pressure thereon and holding it in its pivotally mounted position.

6. The combination with a lamp casing, and a lens therefor, of a tilttable reflector mounted within said lamp casing, yielding means for retaining said reflector normally in tilted position, and a bellows mounted between said reflector and casing adapted to be contracted for overcoming said yielding means for returning said reflector from tilted position.

7. The combination with a lamp casing, 90 and a lens therefor, of a tilttable reflector mounted within the lamp casing, means on the lower edge of said reflector for pivotally supporting it within said casing so as to be tilttable therein, and a bellows mounted between said reflector and casing for controlling the tilting movement of said reflector.

8. The combination with a lamp casing, and a lens therefor, of a reflector within the lamp casing, means on the lower portion of 100 said reflector for pivotally supporting it within said casing, yielding means for engaging said reflector for exerting a downward pressure thereon and support it in tilted position, and a bellows mounted between said reflector and casing adapted to contract and overcome said yielding means for returning said reflector from its tilted position.

In witness whereof, I have hereunto af- 110 fixed my signature.

SAMUEL F. ARBUCKLE.
